J. H. SCHLAFLY.

SILO.

APPLICATION FILED MAY 17, 1913.

1,265,966.

Patented May 14, 1918.

UNITED STATES PATENT OFFICE.

JULIUS H. SCHLAFLY, OF CANTON, OHIO, ASSIGNOR TO THE CANTON CULVERT & SILO COMPANY, OF CANTON, OHIO, A CORPORATION OF OHIO.

SILO.

1,265,966.

Specification of Letters Patent. Patented May 14, 1918.

Application filed May 17, 1913. Serial No. 768,239.

To all whom it may concern:

Be it known that I, JULIUS H. SCHLAFLY, a citizen of the United States, residing at Canton, in the county of Stark and State of Ohio, have invented a new and useful Silo, of which the following is a specification.

My invention relates to improvements in sheet metal structures, and while applicable to structures for various purposes, has special reference to the construction of silos and the like.

The objects of the invention are, to generally improve structures of the character mentioned, to provide a silo or the like which will be strong and durable and thoroughly air and water tight and thus adapted to thoroughly preserve and retain its contents, and to provide a knock-down or sectional construction wherein the various parts or sections are so constructed as to be interchangeable, thus making the erection of the device an easy matter in that said sections need not be put together in any one, predetermined order or arrangement and the means of connection for the various sections being simple and readily understood by unskilled workmen. Additional objects are the provision of air and water tight joints between the various sections, the strengthening of the edges of the sections so as to brace the joints and the protection of the joints by integral protecting flanges.

Various other features of the construction are of much importance and other objects than the above will be apparent to those skilled in the art.

The best mode in which I have contemplated carrying out my invention is illustrated in the accompanying drawings, although it will be understood that the invention may be embodied in other forms.

In the drawings Figure 1 is a side elevation of a silo constructed in accordance with my invention. Fig. 2 is a perspective view of one of the sections used in constructing the silo, a portion being broken away to reduce the size of the figure. Fig. 3 is a fragmentary perspective view, with a portion broken away, to illustrate the manner of connecting the sections.

Throughout the several views similar reference numerals indicate similar parts.

More specifically describing the construction disclosed in the drawings the numeral 1 indicates the wall and the numeral 2 the floor of the foundation for the silo. This

foundation is preferably formed by digging in the earth 3 an annular trench for the wall 1 and digging away the earth within the inner line of said trench to the point 4 below the ground level 5 to accommodate the desired thickness of the floor 2. The foundation is then preferably constructed by pouring plastic concrete into the excavation thus made until the point 6 is reached, then setting into the trench on top of the concrete thus placed the first or bottom annular tier 7 of connected metallic sections. More concrete is then added until the ground line 5 is reached, and is preferably somewhat banked up on the outer side of the bottom tier. The top surface of the floor 2, around the outer edge, should be substantially on a level with the ground line 5, and is preferably somewhat declined from said outer edge to the center.

Attention is now directed to the construction of the metallic sections as particularly illustrated in Figs. 2 and 3. Each section 8 is substantially rectangular and is preferably arranged with its longer dimension extending horizontally. Each section is curved in accordance with the desired circumference of the silo to be constructed and two adjacent edges, preferably the top and one side edge, are provided with the plain out-turned integral flanges 9 and 10 respectively. The opposite or bottom and other side edge are provided with the out-turned flanges 11 and 12 respectively, said flanges 11 and 12 being provided with integral, auxiliary, protecting flanges 13 and 14 respectively, said flanges 13 and 14 extending at right-angles to the flanges 11 and 12 and lying in planes parallel with the body portion of the section 8. The flanges 9, 10, 11 and 12 are all provided with bolt apertures 15 to receive bolts 16 for fastening the sections together.

By reference to Fig. 3 it will be seen that in joining adjacent sections in any one tier the flange 12 is brought face to face with the flange 10 of an adjacent section, the flange 14, formed integrally with the flange 12, extending over the edge of the flange 10 and thus protecting and covering the joint. Between the flanges 10 and 12 packing 17 of any well known material may be arranged before drawing up the bolts 16, said packing serving to produce an air tight joint and being protected and held in place by the protecting flange 14.

When each tier has been connected and ar-

ranged in place the top plain flange 9 of the various sections constituting the tier will form an annular outwardly extending flange upon which the bottom flanges 11 of the sections of the superjacent tier are adapted to rest. Here again packing 17 may be employed to form a tight joint and bolts 16 may be used to fasten the flanges together. The protecting flanges 13 of the various sections extending over the outer edges of the packing 17 and the flanges 9 and 11 as will be especially noted by reference to Fig. 3 produce a dependent water drip adapted to carry any water over and beyond the joint.

15 One important feature of the construction is the strengthening and bracing effect produced by the flanges 13 and 14. By reference to Fig. 3 it will be noted that when the outstanding flanges 9 and 11 and 10 and 12 have been connected to form the horizontal and vertical joints described said flanges serve to thoroughly brace and strengthen the wall of the silo so long as said flanges are maintained in true, outstanding position.

20 The flanges 13 and 14 act as braces for the said outstanding joint flanges, hold the outer edges of said flanges in true alinement and very thoroughly brace them against bending, as well as against relative movement which would not only weaken the structure, but would destroy the effectiveness of the packing 17.

The flanges 11 and 13 of the bottom tier, being embedded in the concrete foundation, 35 provide a thoroughly solid and effective anchor. The first tier of sections is preferably continuous, but the second tier is provided with a door, the third tier is continuous and the fourth tier provided with a door, and in 40 similar manner for the entire height of the silo, alternate tiers being continuous and alternate tiers provided with doors.

Special attention is now directed to the doorway and door construction. In forming the door frame the side pieces 18 are 45 provided, which are formed of sheet metal and are provided with the section-attaching portion 19, the outwardly inclined portion 20, the outer or casing portion 21, the inwardly extending side-pieces 22 and the integral door stop flange 23 extending in line with the body portion of the sections 8. The attaching portions 19 are connected to the sections by means of bolts 16 and on one 55 side of the doorway two vertical hinge-loops 24 are connected by bolts passing through the portion 19 and the body of the section 8.

The door 25 extends from the side piece 22 on one side of the door frame to the 60 similar side piece on the other side and is provided with the integral edge flanges 26 and return flanges 27. The door is formed of a curvature to correspond with the curvature of the sections 8 and closes against the

stop flanges 23, the flanges 26 abutting face 65 to face with the side pieces 22 in the closed position.

Connected to each hinge-loop 24 by means of a barrel portion 28, is a combined hinge, ladder and hasp bar 29 which is connected 70 to the door 25 by bolts 30. It will be noted that said bar 29 snugly over-lies the portions 20 and 21 of the side piece to which it is hingedly attached, extends to the edge of the return flange 27 on the hinged side 75 of the door, where it turns abruptly toward the body of the door 25 to which the bolts 30 connect it. Beyond said bolts said bar 29 turns abruptly outwardly to form the step portion 31 spaced from the body of the door and following in parallel relation to said door to the hasp side, where it turns abruptly, is again connected to the body of the door by bolts 30, then extends outwardly 80 beyond the return flanges 27, where it is again bent into parallel relation to the body of the silo and over-lies said flange 27 and the portion 21 of the door frame. In the hasp portion of the bar 29 which extends beyond the edge flange 26 is a transverse 85 aperture 32, and a bolt 33 connected to the portion 21 of the side piece is adapted to extend through the aperture 32 when the door is in the closed position, a wing nut 34 being employed to clamp the projecting hasp portion to the portion 21.

Each door is preferably provided with two of the bars 29, the tiers intermediate the doors being provided with but a single step 31^a each. In Fig. 1 it will be noted how the 100 various steps produce a ladder for the purpose of climbing up to the appropriate door to enter the silo when desired.

The side walls of the silo having been built to the desired height by arranging one 105 tier of sections upon another, the roof is next attached. Said roof is preferably composed of a plurality of sectoral sections 35. Each of said sections is provided at its lateral edges with up-turned joint flanges 36 110 having integral, auxiliary attaching flanges 37 extending in inclined position down and back toward the body of the section, preferably at an angle of about 45°.

For connecting the various sectoral roof 115 sections connecting strips 38 are provided. Said strips are formed of sheet metal and each strip is equal in length to the length of the flanges 36 of the various sections. The body portion of each strip is bent along a longitudinal line with the body portions on the two sides of said line forming a substantially 90° angle with each other, and therefore adapted to snugly over-lie the attaching flanges 37 of adjacent roof sections 120 in their abutting position. Formed integrally with the body of the strip 38 the marginal, return holding flanges 39 are pro-

vided, which are adapted to extend around the free edges of the flanges 37 and to extend up on the under-side of said flanges to hold the same firmly in position. In connecting the roof sections the strips 38 are slidably connected to the attaching flanges of adjacent roof sections, being preferably connected by sliding movement from the outer, lower ends of said roof sections toward the upper inner ends thereof.

The angular relation of the lateral edges of the roof sections is such as to produce a frusto-conical shaped roof when all of the sections have been connected together, and for the purpose of connecting said sections to the walls of the silo the top flanges 9 of the uppermost tier of sections 8 is bent slightly down at its outer edge, throwing said flange into inclined position, so as to correspond with the pitch of the roof. Bolts 40 are then employed to fasten the flange to the roof sections.

It will be understood that the joint flanges 36 serve to stiffen the roof, and it should be noted that said roof is self-supporting, no frame work in addition to the sectoral sections and connecting strips being necessary.

The sections 35 do not entirely meet in the center, leaving a ventilating opening at 41 and if desired a ventilator 42 of any well known construction may be connected to the roof to shelter said opening 41 while permitting ventilation therethrough.

While the foregoing description presents the best mode in which I have contemplated building silos of the character described, it should, of course, be understood that numerous changes in design and details of construction may be made as experience suggests or circumstances may require without departing from the spirit of the invention, within the scope of the appended claims.

I claim:—

1. A silo formed of a plurality of sheet metal sections, provided with curved body portions and out-turned integral abutting margins arranged to form out-standing horizontal and vertical seams and means for fastening the abutting margins of each seam together, the upper out-turned margin of each horizontal seam and one of the out-turned margins of each vertical seam provided with an integral auxiliary portion disposed parallel to the adjacent body portion of the section, extending over the edge of the other out-turned margin of the seam, and adapted to protect, stiffen and brace the same, and said upper out-turned margin of each horizontal seam being sufficiently wider than the out-turned margins of said vertical seams to permit the horizontally disposed auxiliary portion thereon to overhang the upper ends of the sub-jacent vertical seams

including the integral auxiliary portions thereof.

2. A silo formed of rectangular sheet metal sections arranged in annular tiers, the sections in each tier provided at their vertical edges with integral out-standing, abutting, connected flanges forming vertical joints, and said sections also provided at their horizontal edges with integral, out-standing flanges; the out-standing flanges on the lower horizontal edges being provided with auxiliary, depending, portions, said depending portions being continuous in each tier and overhanging the outermost edges of the flanges forming said vertical joints.

3. A silo formed of a plurality of sheet metal sections arranged in annular tiers, the sections forming each tier being united by integral, out-standing flanges forming vertical joints and adjacent tiers being connected by integral out-standing flanges forming horizontal joints, and the super-jacent flange of each horizontal joint extending beyond and having a depending portion overhanging the sub-jacent flange of said horizontal joint and also the flanges forming the vertical joints in the sub-jacent tier.

4. A silo formed of a plurality of sheet metal sections arranged in tiers and connected together by integral, out-standing marginal flanges forming vertical and horizontal joints, the upper flange of each horizontal joint being provided with an integral depending portion overhanging and protecting the lower flange of said joint and the flanges of the vertical joints in the sub-jacent tier as well.

5. A silo section formed of sheet metal and comprising a rectangular body portion and integral marginal flanges on the four edges of the same, two of said edges adapted to be disposed vertically and two horizontally, one of the vertical flanges provided with an integral auxiliary portion extending in a plane parallel to said body portion and the lower horizontal flange being wider than the other marginal flanges and provided with an integral auxiliary portion depending in a plane parallel to said body portion, whereby when the plurality of such sections are connected together with their margins abutting, said auxiliary portion on said lower horizontal flanges will extend over and protect the upper ends of said vertical flanges, including their integral auxiliary portions.

In testimony that I claim the above, I have hereunto subscribed my name in the presence of two witnesses.

JULIUS H. SCHLAFLY.
